UNITED STATES PATENT OFFICE.

ARTHUR ROBERT KRAUSE, OF WOODHAVEN, NEW YORK, ASSIGNOR TO LION ELECTRIC MANUFACTURING CO., INC., A CORPORATION OF NEW YORK.

DESIGN FOR A WALL BRACKET FOR WALL LIGHTS.

Application filed October 7, 1924. Serial No. 10,988. Term of patent 7 years.

To all whom it may concern:

Be it known that I, ARTHUR ROBERT KRAUSE, a citizen of the United States, residing at 3966 Fulton Street, Woodhaven, Long Island, county of Queens, city and State of New York, have invented a new, original, and ornamental Design for a Wall Bracket for Wall Lights, of which the following is a specification, reference being had to the accompanying drawing, which forms a part of this application, and illustrates my design applied to a wall bracket for wall lights.

In the drawing, Fig. 1 is a side elevation and Fig. 2 is a front elevation, both of an embodiment of the design.

I claim:—

The ornamental design for a wall bracket for wall lights, as shown.

ARTHUR ROBERT KRAUSE.
